UNITED STATES PATENT OFFICE.

SECONDO L. CASELLA, OF NEW YORK, N. Y.

DESIGN FOR A CASING FOR PNEUMATIC CLEANING DEVICES.

43,717.

Specification for Design.

Patented Mar. 18, 1913.

Application filed May 9, 1912. Serial No. 696,244. Term of patent 14 years.

To all whom it may concern:

Be it known that I, SECONDO L. CASELLA, a citizen of the United States, residing in the borough of Manhattan, city of New York, in the county of New York and State of New York, have invented a certain new, original, and ornamental Design for a Casing for Pneumatic Cleaning Devices, of which the following is a specification, reference being had therein to the accompanying drawings, forming part thereof.

Figure 1 is a top view of my pneumatic cleaning device showing my design. Fig. 2 is a side view of the same.

I claim:

An ornamental design for a casing for pneumatic cleaning device as shown.

SECONDO L. CASELLA.

Witnesses:

VICTOR D. BORST,
BERNARD COWEN.
